Primary Examiner — T Chase Nelson*Assistant Examiner* — Jonathan J. Han(74) *Attorney, Agent, or Firm* — Reed Smith LLP; Nina Habib Borders(57) **CLAIM**

The ornamental design for a tread for a shoe sole, as shown and described.

DESCRIPTION

FIG. 1 is a first perspective view for a tread for a shoe sole showing my new design;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a second perspective view thereof.

The broken lines showing the remainder of the shoe are for illustrative purposes only and form no part of the claimed design.

1 Claim, 4 Drawing Sheets(56)
